CLAIM

We claim the ornamental design for an automotive vehicle rear door and quarter trim panel, as shown and described.

DESCRIPTION

FIG. 1 is a perspective view of an automotive vehicle rear door and quarter trim panel, of the new design;

FIG. 2 is a front view thereof;

FIG. 3 is a top view thereof;

FIG. 4 is an edge view thereof;

FIG. 5 is an edge view thereof, opposite that of FIG. 4;

FIG. 6 is a bottom view thereof; and,

FIG. 7 is a back side view thereof.

The stippled portions indicate a darker color than the non-stippled portions on and immediately above the arm rest portions. The broken and dotted lines in FIG. 7 indicate portions internal thereto which form no part of the claimed design. The broken and dashed lines are for environmental illustrative purposes only and form no part of the claimed design.

1 Claim, 6 Drawing Sheets
